UNITED STATES PATENT OFFICE.

ERNEST F. ROWLEY, OF BIRMINGHAM, ALABAMA.

GRATE-BAR.

1,175,823.

Specification of Letters Patent. Patented Mar. 14, 1916.

Application filed October 15, 1912. Serial No. 725,894.

To all whom it may concern:

Be it known that I, ERNEST F. ROWLEY, a citizen of the United States, residing at Birmingham, in the county of Jefferson and 5 State of Alabama, have invented new and useful Improvements in Grate-Bars, of which the following is a specification.

This invention relates to grate bars for furnaces and fire boxes, and it has for its object to produce a grate bar unit of simple 10 and inexpensive construction which shall possess superior advantages in point of durability and general efficiency.

Various means have heretofore been resorted to for the purpose of lengthening the 15 life of grate bars in view of the intense and variable heat to which they are subjected. Thus, for instance, so called "reversible" grate bars have been made on the supposition 20 that after one surface of the bar has become burnt or deteriorated by use, the life of the bar might be lengthened by upending or reversing the same so as to expose a fresh surface for active use. Practically, 25 however, it is found that the reversal of a grate bar is practically impossible in a majority of instances, because any injury to a grate bar, whether caused by burning, cracking or other reasons, is almost invariably 30 accompanied by warping, whereby the grate bar is distorted so as to make reversal thereof impossible. Again, if the grate bar is already weakened by burning or cracking, merely reversing it will not strengthen it to 35 the extent of enabling it to withstand wear and usage which it would not withstand prior to being inverted.

By the present invention I aim to produce a nonreversible grate bar possessing great 40 strength and wear resisting qualities, the same being reinforced and strengthened throughout where reinforcement and strength is needed, while parts not subjected to hard usage are left comparatively light 45 in order to save material.

A further object of the invention is to produce a hollow or tubular grate bar reinforced at the top and having a fuel supporting surface provided with draft apertures 50 of relatively small size, while the sides and bottom of the bar are provided with relatively large openings through which ashes, clinker-forming material and other waste will escape to the ash pit without possibility 55 of accumulating in any obstructing position.

A further object of the invention is to

produce a grate bar unit having terminal supporting lugs formed by extensions of the reinforced or thickened portion which will be sufficiently heavy and massive to resist 60 the changes of temperature to which they will be subjected without rapid deterioration.

A further object of the invention is to produce a hollow tubular grate bar unit of 65 octagonal cross section having one flat top surface to support the fuel and to guide the cleaning hoe which is used to clean the fire; two inclined surfaces coöoperating with the central flat top surface to support the fuel 70 and coöoperating with the corresponding surfaces of proximate grate bar units to form pockets for the reception of partly consumed fuel, the combustion of which will be completed in said pockets; two vertical side 75 faces having relatively large elongated openings partly for the circulation of air and partly to lighten the structure, the strength of which, however, remains practically unimpaired owing to the fact 80 that the structure is trussed and reinforced by the filling material between the openings; and three bottom faces which are lightened by numerous apertures of relatively large size which permit the circulation 85 of air while not obstructing the passage of material dropping through relatively small draft openings in the top surfaces of the bar.

A further object of the invention is to 90 produce a tubular grate bar unit having openings throughout for the circulation of air, the said bar being reinforced in such a fashion as to practically preclude warping.

With these and other ends in view which 95 will readily appear as the nature of the invention is better understood, the same consists in the improved construction and novel arrangement and combination of parts which will be hereinafter fully described and particularly pointed out in the 100 claims.

In the accompanying drawing has been illustrated a simple and preferred form of the invention, it being, however, understood 105 that no limitation is necessarily made to the precise structural details therein exhibited, but that changes, alterations and modifications within the scope of the claims may be resorted to when desired.

In the drawing, Figure 1 is a top plan view of a grate bar unit constructed in ac-

cordance with the invention. Fig. 2 is a side elevation. Fig. 3 is a bottom plan view. Fig. 4 is a vertical transverse sectional view showing a plurality of units juxtaposed.

5 Corresponding parts in the several figures are denoted by like characters of reference.

The improved grate bar unit shown in the drawing is a hollow bar or tube A which has been represented as being externally 10 of regular octagonal shape in cross section, having eight equal sides. It is to be understood, however, that this regular shape may be departed from by making the sides unequal, although it is preferred that a symmetrical shape be retained. The top portion 15 of the bar is greatly thickened and reinforced, as shown at 1, the reinforcement being included between the top face 2 of the octagon and a plane 3 which is preferably 20 below the inclined faces 4, 4 adjacent to the top face 2. The remaining walls of the structure, including those which are externally bounded by the side faces 5, 5, the bottom face 6 and the inclined faces 7, 7 25 adjacent to the bottom face are preferably of equal thickness throughout, being made as light as may be consistent with the necessary strength. The thickened or reinforced top portion 1 of the bar is provided with 30 draft openings 8, said draft openings preferably having vertical side walls so that ashes and other waste material may sift or pass unobstructedly therethrough. The side walls 9, which are externally bounded by the 35 side faces 5, are provided with elongated openings 10. Elongated openings 11 of relatively large area are also formed in the bottom wall 12 and in the inclined walls 13 which are externally bounded by the bottom 40 face 6 and the inclined faces 7, respectively. The openings 11, while elongated, are also of relatively great width, each of said openings being formed partly in the bottom wall and partly in one of the inclined walls 13. 45 The bottom wall 12 is preferably reinforced by a longitudinal rib or web 14 formed on the upper face thereof, interiorly of the tubular bar. The side walls 9 are provided at intervals with external spacing lugs 15 50 whereby proximate grate bars will be suitably spaced apart, as clearly seen in Fig. 4, to permit draft to pass upward between the grate bar units and to permit clinker-forming material, ashes and other waste to pass 55 therebetween.

The grate bar unit is provided at each end thereof with a supporting lug 16 formed by an extension of the thickened reinforced top portion 1, the entire cross sectional area 60 of which is retained throughout said lugs which are for the purpose of supporting the bar unit on the furnace walls or on the supporting frame provided for the purpose, as will be readily understood.

65 The use and advantages of the improved

grate bar units will be readily understood from the foregoing description, taken in connection with the drawing hereto annexed, by those skilled in the art to which the invention appertains. It is desired to be 70 understood that the draft apertures 8 extending through the reinforced portion 1 of the grate bar unit, and the upper ends of which communicate with the top face 2 and with the inclined faces 4, may be of 75 any desired contour and dimensions which will be governed entirely by the character of fuel that is to be consumed. The fuel will be supported mainly on the top face 2 and on the inclined faces 4, and it will 80 be seen that the inclined faces 4 of each grate bar unit coöperate with the corresponding faces of proximate grate bars to form V-shaped pockets into which partly consumed fuel will drop when the fuel is 85 agitated by the rake or slice bar, thus permitting the combustion to be completely carried out, the combustion of the fuel material in said pockets being supported by the air currents rising between the grate bars. 90 Large quantities of air will also enter the tubular grate bars through the large openings 11 and 10 in the inclined walls 13 and in the side walls 9, the air on entering the hollow spaces being heated preliminary to 95 ascending through the draft apertures 8.

It is obvious that any material, such as ashes or clinker-forming material, sifting or passing through the relatively small openings 8 will readily pass through the large 100 openings 11 and into the ash pit. The flat top face 2 of the grate bar unit will readily support the rake or the slice bar used for cleaning the fire, and keep such tool clear of the pockets between the inclined faces 4 of 105 proximate grate bars, thus enabling the fire to be cleaned without disturbing and wasting the partly consumed fuel which may be contained in said pockets. It will be seen that by far the greatest thickness of material is found in the top of the grate bar unit which is subjected to the most intense heat and where thickness and strength is obviously needed. The side walls of the bar unit, as well as the bottom wall 12 and the 110 inclined walls 13, are of relatively light construction, this being made possible, owing to the fact that these portions of the bar unit are maintained in a relatively cool condition by the currents of air entering from 115 below. The side walls, moreover, constitute what may be practically regarded as truss structures, the struts being formed by the solid metallic portions adjacent to the ends of the oblong openings. The bar is thus 120 greatly reinforced against any possibility of warping or bending in any direction.

125 It is desired to be understood that the term "solid" as herein used is mainly used in contradistinction to "hollow". Thus, the 130

- reinforced, thickened top portion of the 5 grate bar is regarded as solid in the sense that, while provided with draft apertures, it has no hollow portions. In a like sense, the extended ends of said thickened, reinforced top portion and which are utilized as supporting members to support the weight of the grate, are "solid", and not weakened in any part thereof.
- 10 Having thus described the invention, what is claimed as new, is:—
1. A tubular grate bar unit having a greatly thickened and reinforced solid top portion included between and bounded by a flat top face, inclined side faces adjacent thereto, vertical side faces adjacent to the inclined side faces, and a flat bottom face which is parallel to the top face, said grate bar unit having also side and bottom wall portions,
  - 15 20 25 the solid top portion being provided with relatively small draft apertures and the side and bottom wall portions which are relatively thin being provided with relatively large draft apertures.
  2. A tubular grate bar unit having a greatly thickened and reinforced solid top portion included between and bounded by a flat top face, inclined side faces adjacent thereto, vertical side faces adjacent to the inclined side faces, and a flat bottom face which is parallel to the top face, said grate bar unit having also side and bottom wall

portions, the solid top portion being provided with relatively small draft apertures and the side and bottom wall portions which are relatively thin being provided with relatively large draft apertures; the thickened and reinforced top portion being terminally extended to form solid supporting lugs.

3. A tubular grate bar unit having a greatly thickened and reinforced solid top portion included between and bounded by a flat top face, inclined side faces adjacent thereto, vertical side faces adjacent to the inclined side faces, and a flat bottom face which is parallel to the top face, said grate bar unit having also side and bottom wall portions, the solid top portion being provided with relatively small draft apertures, and the side and bottom wall portions which are relatively thin being provided with relatively large draft apertures; the thickened and reinforced top portion being terminally extended to form solid supporting lugs, and the bottom wall portion being provided on its upper face with a reinforcing rib extending longitudinally through the tubular bar unit.

In testimony whereof I affix my signature in presence of two witnesses.

ERNEST F. ROWLEY.
